UNITED STATES PATENT OFFICE.

OTTO SCHEIB, OF BARMEN, GERMANY, ASSIGNOR TO A. STEINHARDT & BRO., INC., OF NEW YORK, N. Y., A CORPORATION OF NEW YORK.

HAIR CURLER.

Application filed June 8, 1923. Serial No. 644,073.

To all whom it may concern:

Be it known that I, OTTO SCHEIB, a citizen of the Republic of Germany, residing at Barmen, Prussia, Germany, have invented certain new and useful Improvements in Hair Curlers, of which the following is a specification.

My present invention relates to flexible hair curlers adapted to be bent or twisted after the hair has been wound around the curler so as to keep the curler and subsequently the hair thereon in a fixed condition during the curling process.

My invention will be best understood from the following description and the annexed drawing, in which Fig. 1 is a side view of one form of hair curler embodying my invention; Fig. 2 is a view similar to Fig. 1, but with the right-hand portion of the figure cut on a longitudinal plane and the central portion with the outer covering only removed, and Fig. 3 is a section through one of the enlargements of the curler shown in Figs. 1 and 2.

Like reference characters indicate like parts in the several views.

The illustrative form of curler has a metallic core 10 preferably of lead, around which is wound a covering of strands, this covering with the wire 10 forming a gimp filling of the curler. In the form illustrated, this covering for the metallic core is cylindrical at the central portion 11 of the curler, but adjacent either end there is an enlargement 12 from which the filling again is reduced in diameter at the end portions 13, these portions preferably being smaller in diameter than the central portion 11.

Over the covering is a flexible sheath 14, the ends of which may be held in place by a metallic or wax holding device 15. This

holding device forms no part of my invention and will be understood by those skilled in the art.

By forming the enlargements 12, 12, the hair wound around the central portion 11 is prevented from sliding longitudinally along the curler as it might do if the ends of the curler were tapered and not provided with these enlargements. Moreover, the curler, after the hair has been wound on the central portion, may be bent until the enlargements 12, 12 are in contact with each other, and then the relatively small end portions 13 may be wrapped around each other to lock the curler securely in position.

I claim:

1. As a new article of manufacture, a hair curler having a gimp filling therefor comprising a long core of soft metal and thread wound tightly thereon, with enlargements of the filling near either end of the core, and removed from the ends of the curler and a flexible sheath covering the filling.

2. As a new article of manufacture, a hair curler having a long core of soft metal, thread wound tightly thereon, with the central portion cylindrical and enlargements of the filling at the end of the central portion and removed from the ends of the curler, and a flexible sheath covering the filling.

3. As a new article of manufacture, a hair curler having a long core of soft metal, thread wound tightly thereon, with the central portion cylindrical and enlargements of the filling at the end of the central portion and removed from the ends of the curler and with the ends smaller in diameter than the central portion, and a flexible sheath covering the filling.

OTTO SCHEIB.
